UNITED STATES PATENT OFFICE.

MAHLON A. STRIPE, OF GENEVA, ILLINOIS.

RAIL-JOINT.

1,021,013.

Specification of Letters Patent. Patented Mar. 26, 1912.

Application filed May 17, 1911. Serial No. 627,657.

To all whom it may concern:

Be it known that I, MAHLON A. STRIPE, a citizen of the United States, and a resident of the city of Geneva, county of Kane, 5 and State of Illinois, have invented certain new and useful Improvements in Rail-Joints, of which the following is a specification.

My invention relates to improvements in 10 rail-joints, the object of the invention being to provide a rail-joint which shall be simple of construction and efficient in operation.

A further object of my invention is to provide a rail-joint which shall be so designed and constructed as to be readily taken apart without the use of bolts or other detachable securing means.

Other objects will appear hereinafter.

With these objects in view my invention 20 consists in the novel construction and arrangement of parts all as will be hereinafter more fully described and particularly pointed out in the appended claims.

My invention will be more readily understood by reference to the accompanying drawings forming a part of this specification, and in which,

Figure 1 is an end elevation of a rail end embodying my invention, Fig. 2 is a 30 side elevation of said rail end, Fig. 3 is an end elevation of a securing member employed in the rail-joint, Fig. 4 is an inside view of said securing member taken before the same is applied to the rail, Fig. 5 is 35 an inside view of a second securing member taken before being applied to the rail, Fig. 6 is an end elevation of said last-named securing member, and Fig. 7 is a top plan view of the assembled rail-joint.

40 The preferred form of construction of my invention as illustrated in the accompanying drawings comprises an ordinary rail having a base 1, web 2, and head 3, there being no bolt-holes or any special 45 formation of the rail preparatory to making the rail-joint. The rail securing means which will be presently described is applied to each end of all of the rails of a track, hence it is only necessary to describe 50 the construction of such means as applied to one rail end. Broadly the securing means comprises intermeshing fingers and sockets provided on the rail ends, and more specifically securing members or plates 55 in which said fingers and recesses are formed. One of said securing members

which is applied to one side of a rail comprises a finger 4 extending longitudinally from a plate 5, there being recesses 6 provided on either side of said finger in the body of said plate. At one end of said recesses flanges 7 are provided the edges of which lie in the same plane as the interior surface of the finger 4. The lateral edges 8 of the plate 5 are beveled as shown in Figs. 3 and 4, the angle of the bevel corresponding with the bevels of the base 1 and head 3 of a rail end. In forming the joint the plate 5 is inserted between the base 1 and head 3 of the rail and electrically welded in position, the line of the weld being indicated by dotted lines in Fig. 1. On the opposite side of the rail end a plate 9 similar to the plate 5 is provided, the main difference being that two fingers 10 are provided instead of one finger 4 in plate 5. Also in this plate there is a single recess 11 located between the fingers 10, this recess being designed to receive a finger 4 of a rail to which this rail is jointed. A flange 12 similar to the flange 7 closes the end of the recess 11. Bevel edges 13 are provided on this plate which fit between the base 1 and head 3 of the rail on the opposite side thereof from that to which plate 5 is welded. Plate 9 is now welded in position as indicated by dotted lines in Fig. 1, the resulting rail having three fingers and three sockets, as each end of each rail is provided with the two plates.

It is apparent from the foregoing description that in order to unite any two given rail ends provided with fingers and sockets according to my invention it is only necessary to press the fingers into the sockets provided therefor until the rail ends are contiguous, there being no bolts or other detachable securing means, and the spiking of the rails of the rail ties being depended on to prevent creeping and for holding the rails in position.

A rail-joint designed and constructed as set forth is simple of construction and highly efficient in operation.

While I have illustrated and described the preferred form of construction for carrying my invention into effect, this is capable of variation and modification without departing from the spirit of the invention. I therefore do not wish to be limited to the precise details of construction set forth, but desire to avail myself of such variations and

modifications as come within the scope of the appended claims.

Having described my invention what I claim as new and desire to secure by Letters

5 Patent is:

1. In a rail-joint, a member comprising a finger and two finger-sockets welded to one side of a rail end, and a member comprising two fingers and a finger-socket 10 welded to the opposite side of said rail end, substantially as described.

2. In a rail-joint, a member comprising a finger and two finger-sockets electrically welded to one side of a rail end, and a member comprising two fingers and a finger-socket electrically welded to the opposite side of said rail end, substantially as described.

3. In a rail-joint, a member having a finger, two sockets, and two bevel edges fitted and welded to a side of a rail at the

end thereof, and a second member having two fingers, one socket, and two bevel edges fitted and welded to the other side of the rail end, substantially as described.

25

4. In a rail joint, a member having a finger, two sockets, and two bevel edges fitted and welded to a side of a rail at the end thereof, and a second member having two fingers, one socket, and two bevel edges 30 fitted and welded to the other side of the rail end, said sockets being disposed substantially opposite said fingers, substantially as described.

In testimony whereof I have signed my 35 name to this specification in the presence of two subscribing witnesses.

MAHLON A. STRIPE.
